METHOD OF TREATING AND USING
PLYWOODHerman J. Ries, New York, N. Y., assignor to
Percy W. Valentine, Brooklyn, N. Y.

Application March 19, 1938, Serial No. 196,872

12 Claims. (Cl. 93—40)

This invention relates to the production of a new article of manufacture by the method of treating and facing plywood to adapt the resulting article to many uses, and particularly in producing irregular or curved contours or wall structures from the treated and faced laminated plywood, and the object of the invention is to provide a method of preparing a sheet or strip product of the character described by securing to a strip or sheet of plywood one or two facings of canvas or other fibrous material in a manner which will render the resulting product soft and pliable throughout to adapt it to relatively sharp bending, folding or shaping, thereby permitting the use of the product for producing wall structures of irregular contour and design, a further object being to produce worksheets or pieces of predetermined shape and contour and then attaching the canvas or other facings thereto to provide free flanged edges of the facings beyond the edges of the workpiece to facilitate attachment of the sheet to other wall portions disposed angularly to or extending from the edge of the worksheet to reinforce the attachment of the sheets one with respect to the other or the mounting of the workpiece in connection with another support, and with these and other objects in view the invention consists in the method of making articles of manufacture of the character described as more fully hereinafter set forth and adapted for use in the production of merchandise as hereinafter described.

The invention is fully disclosed in the following specification, of which the accompanying drawings form a part, in which the separate parts of my improvement are designated by suitable reference characters in each of the views, and in which:

Fig. 1 is a perspective view of the part of a sheet of canvas or similar fabric material employed as a facing element.

Fig. 2 is a view similar to Fig. 1 showing a plywood strip or sheet to which the facing of Fig. 1 may be attached.

Fig. 3 is a sectional detail view showing the facing of Fig. 1 attached to a plywood strip as in Fig. 2.

Fig. 4 is a view similar to Fig. 3 showing two facings applied to the plywood.

Fig. 5 is a view similar to Fig. 4 showing two different types of facings on the plywood.

Fig. 6 is a sectional and partially perspective view diagrammatically illustrating one method of using the articles produced according to my invention.

Fig. 7 is a perspective view of another form of article illustrating another use of my invention.

Fig. 8 is a partial section on the line 8—8 of Fig. 7 on an enlarged scale, and

Fig. 9 is a view similar to Fig. 8 showing another step in the production of a box or case.

In the art of shaping wood strips or sheets of various kinds and classes, it has been a common practice to steam or otherwise moisten a sheet to render it soft for the purpose of shaping the same and then to shape the sheet in molds, forms or presses. This practice, however, has been costly and furthermore unsatisfactory in that the resulting article would become distorted, have a tendency to crack or break down and furthermore has been limited with respect to its uses; that is to say sharp bends or small radius curves could not be satisfactorily produced in the finished product.

In overcoming these objectionable features, I preferably use a relatively thin plywood, a piece of which is shown at 10 in Fig. 2 of the drawing. This wood in the construction shown consists of an upper and lower ply 10a, 10b and an intermediate ply 10c. While several types of wood may be used in the construction of the plywood 10 and any number of laminations or plies may be provided within certain limits, I have found that where excessive bending and shaping is desired, the best results are obtained in the use of plywood construction from birch. This is especially true of plywood purchased from Finland. This Finland birch can be supplied in very thin sheets of three-ply thickness and will permit a substantial right angle bending or other free formation of the sheet so as to adapt it for many uses as more fully hereinafter set forth.

In carrying out my method I also employ one or two facing sheets 11, 12, a single sheet being used as in Fig. 3 and a double sheet as in Fig. 4. These sheets may be composed of canvas, buckram or other fibrous material depending upon the use to which the invention is applied and may be composed of muslin, linen, etc. In Fig. 5 of the drawing I have shown a sheet, for example like the sheet 11, on one surface of the plywood, whereas a sheet 13 of contrasting material, thickness, color or the like is disposed upon the other surface, and in order to distinguish the facing 11 from the facing 13, the latter facing is shown thicker.

In producing products such as shown in Figs. 3, 4 and 5 in accordance with my method, I first prepare a paste for securing the facing sheets 11, 12 and 13 to the plywood 10. This paste,

for example, may consist of flour, patent paste, salt, ether and water, the relative proportions being as follows: 10 lbs. of flour, 5 lbs. of patent paste, 1 lb. of salt, 16 fluid ozs. of ether and 2 quarts of water. It will of course be understood that the exact proportions of the ingredients and the exact ingredients are not absolutely necessary for producing the desired results, as the illustration given is only to demonstrate a practical method of carrying my invention into effect. It is also desirable to prepare the paste or adhesive in the form of a fairly thick mass prior to adding the ether thereto, and the ether may be added to dilute the paste to a proper consistency, or additional water may also be added for this purpose.

I also use a solution consisting of substantially 5 lbs. of washing soda to 2 qts. of water. In carrying my invention into effect, the soda solution is first applied to both surfaces of the plywood 10 by means of a brush or other applicator to fully saturate both surface of the plywood. A number of boards or sheets similar to 10 may be so treated and allowed to remain under a cover or press for a period of about five minutes so as to avoid quick drying and distortion of the sheet.

I next apply the paste to the surface of the fabric sheet which is to be arranged adjacent the board 10. This sheet is then stretched, pulled or otherwise smoothed on one surface of the plywood 10. Suitable rollers may be used for this purpose if desired, although in handling small sheets the hands of an operator will be sufficient.

In attaching the sheet 11 to the board 10, in certain uses of the invention, it is desirable to allow the edge or edges of the sheet 11 to protrude beyond the edge or edges of the board 10 as seen at 11a. This may also be true of the sheet 12 as seen at 12a and the sheet 13 as seen at 13a. If the double-facing 11, 12 is to be used as in Fig. 4, it will be understood that the sheet 12 is treated and applied in the same manner as the sheet 11. This also applies to the construction shown in Fig. 5 where the sheets 11 and 13 are applied.

After the desired facing or facings are attached to the board 10, the product thus produced is then immediately placed in a suitable form, die, mold or the like may immediately be wrapped around or attached to an irregular surface for which it is to constitute a facing. In some instances the resulting product may be simply put in a press and dried, or left straight for producing straight or flat walled structures of a reinforced type. However, my invention relates primarily to constructing worksheets of the character under consideration which are capable of being formed into curved or irregular contours and which will remain in the contours desired.

The worksheets or parts of the plywood as well as the facing or facings will be cut to the contour of the particular product to be formed. This will be done preferably before the facings are applied to the plywood, thus producing workpieces which will serve definite purposes. These workpieces when placed in the press, mold, or the like to shape the same, are allowed to dry, either under natural conditions or by the application of heat or by placing the same in a heated room or compartment. When properly dried, the same may be utilized in the construction of the particular article in question, as for example the articles diagrammatically illustrated in Figs. 6 and 7.

In Fig. 6 is shown a diagrammatic illustration of two suitcase parts and the worksheets producing predetermined wall structures of said parts are illustrated at 14 and 15 by a single cross section to simplify the illustration. It will be understood, however, that these parts represent, for example, the workpiece produced as in Fig. 4; that is to say the plyboard having the two facings 11 and 12 thereon. In one instance the worksheet forms a side wall 16 and integral end walls 10 16a of a cover part 17 of a case whereas, in the other instance, the worksheet forms a side wall 18 and integral end walls 18a of a case part proper 19. The walls 16, 16a, 18, 18a are secured to independent top and bottom walls through the medium of the flanges of the sheets, one of which is shown at 12a in Fig. 6 and one of said walls being indicated at 20.

From the foregoing it will be understood that the workpiece forming the side and end walls of the cover and case parts 17, 19 may simply be placed in a press or form which will curl the ends of the sheet to produce the integral end wall parts 16a, 18a, and allowing these parts to dry sufficiently to permit their attachment to the top and bottom walls in completing the formation of the cover and case parts after which the entire suitcase will have additional facings and trimmings as well as the hardware applied thereto in accordance with conventional practices.

Differentiating from the structure of Fig. 6, I have shown in Fig. 7 one part of a box or suitcase 21 which is constructed from a workpiece or strip made according to my invention, especially as taught in Fig. 4, to form a top wall 22, side walls 22a and a bottom wall 22b of the case 21, the worksheet being placed around a suitable form or block of a contour similar to that shown in the resulting case 21, and so as to form the rounded upper corners 23 and sharper lower corners 24. The ends of the workpiece are joined at any convenient point, for example as indicated in dotted lines at 25, which point of juncture may be reinforced in any desired manner. Part of this reinforcement may consist of a protruding flange 25a of the facing sheets, for example the sheets 11, 12 being disposed in overlapped position at the seam 25.

With the construction shown in Fig. 7 the side wall 26 of the case part is attached to one side edge of the wall portions 22, 22a, 22b. In accomplishing this result, the outer facing 11 of the workpiece for example, may have its flange 11a extend onto the outer surface of the wall 26, whereas the flange 12a of the inner facing 12 will be disposed on the inner surface of the wall 26. With this construction and especially in making large boxes or cases, the flanges 11a, 12a at the other side of the walls 22, 22a, 22b are wrapped around and secured to a reinforcing wire 60 or rod 27 disposed upon the inner surface of the open side of the box or case 21. In other words, it will be understood that the method of attaching the top, bottom and end walls of the part 21 to the side wall 26 will be the same as the attachment of the top and bottom walls, for example the wall 20 with the case parts 17, 19 in the structure shown in Fig. 6.

In Fig. 9 of the drawing I have indicated a corner construction of the case as seen in Fig. 8, showing outer facings 28, 29 applied to the wall parts 22, 26 in addition to a reinforced corner strip of leather or other reinforcing material as at 30, which is stitched by wire stitching or the like as at 31 to the wall parts. However, this

deals with the final trimming of the suitcase or other product. This, as previously stated, forms no direct part of the present invention, it being understood that inner facings or trimmings of 5 various kinds and classes may also be used.

The purpose of the two illustrations in Figs. 6 and 7 of the drawing is to show certain adaptations of my invention in forming what is commonly referred to as suitcases or traveling bags 10 wherein the large side walls of the case and end walls are integrally united in a workpiece made according to my invention. On the other hand, as in Fig. 7, the side wall may be of the usual or any desired construction, and the top, end and 15 bottom walls are united. In some instances the bottom wall may also be separably formed and the workpiece made according to my invention may terminate at the corners 24.

The two illustrations in the accompanying 10 drawing show what may be termed simple adaptations of the invention, it being understood that my improved workpieces may be utilized in the formation of cases, containers or the like of any kind or class and of many irregular contours, 15 such for example as in producing mandolin, banjo, guitar and similar musical instrument cases and cases for other instruments of the irregular shapes and forms governed by the contour of the instrument to a large degree, and also 20 in producing articles of manufacture apart from the use as containers. For example, the invention may be utilized in the construction of walls of buildings of irregular contour and in constructing display devices such as displays for various types and kinds of exhibits, window displays 25 and the like.

In this connection it will be understood that when the worksheet has been permitted to dry in a given shape and contour controlled by the use 30 of forms, molds, dies, frames or the like, the resulting formed workpiece will maintain its shape and contour unless subjected to an excessive amount of moisture. This is especially true when the curved or irregular shaped wall structure of 35 the article is supported in conjunction with other walls or is arranged within outer facing sheets or other protective coatings.

The peculiarity of an article or workpiece made according to my invention lies in the fact that 40 when once shaped into the desired irregular contour, the same will not become warped or distorted when exposed to varying temperature conditions to which articles of this type may be normally subjected.

It is conceivable however, that my invention 45 may be utilized in the construction of boats, canoes and the like by the application of suitable inner and outer protective layers of coating materials which will prevent moisture from contacting the worksheet employed, it being understood that the usual type of reinforcements will be provided in manufacturing devices or articles of manufacture of any kind or class.

It will also be apparent that my improved product 50 may be utilized in the construction of the body portions or wall structures of various types and kinds of vehicles such as aeroplanes, trailers and the like.

In the construction of luggage, one of the distinctive advantages of my invention resides in the 55 fact that very light-weight or so-called aeroplane luggage can be produced, and yet the resulting suitcase or other container constituting the luggage will be strong and durable and will maintain its shape and contour, and still further

can be produced at a nominal cost. I have produced cases wherein the plywood as at 10 is $\frac{3}{2}$ nd of an inch or less in total thickness. It will thus be seen that a complete case including one or two of the facings together with the additional trimmings and reinforcements will naturally be considerably less in weight than other articles of this type. In view of the strength in the wall structure of the box made according to my invention, I have found that thinner facing or 10 trimming fabrics can be used.

Where the question of weight is not a factor, a thicker plywood and an additional number of plies in the plywood may be provided. However, I have found from experience that thick plywood 15 running above $\frac{3}{4}$ ths of an inch cannot be employed and in fact best results are obtained with plywood not much greater than $\frac{3}{2}$ nds in thickness.

Another distinctive feature of my invention, 20 for example in the construction of luggage, the stitchings as at 31 may be disposed closer to the corners than in conventional practices, first by reason of the fact that reinforced corner pieces are eliminated and further by reason of the 25 sharp inner corners produced by my process. This effects a saving in the width of the outer reinforcing strips 30 employed and the resulting saving in weight in the entire piece of luggage. It will of course be understood that suitable 30 reinforcing strips will be provided for reinforcing the mounting of hardware such as handles, locks, catch devices and the like in connection with the thin walled structure, but such reinforcements are also well known in this art.

In order that the characteristics of my product 35 may be understood and especially in its assembled state prior to placement in the forming means, such for example as a press, die, or frame, it will be understood that the entire product is so soft and pliable as to be readily bent in substantially any shape to dispose adjacent sections in angular relationship with respect to each other so that the product can actually be die formed, 40 provided the structure of the die will not necessitate drawing of the material to any appreciable degree. I have thus found that the sharp bending and many irregular contours can be produced without the result of cracking or splitting the plywood when the resulting product is dry.

This is especially true in utilizing thin plywood 45 of the Finland birch type.

It will be understood that the consistency of the paste or binder utilized for adhering or uniting the facings 11, 12 and 13 may be varied to 50 suit the particular type and kind of facing employed. However, I have found in using a paste substantially of the kind herein mentioned that an adhesion or binding is effected between the saturated plywood and the facing sheet when 55 cemented or pasted thereto and allowed to dry in the contour defined by the press, mold, frame or die employed.

In the production of small articles of manufacture and where the necessity of utilizing protruding flanges on the workpieces is not essential, it 60 will be understood that large worksheets may be produced in the single or double-faced types in accordance with the teachings in Figs 3, 4 and 5. Then these worksheets may be die or otherwise cut into a series of independent workpieces, and separate binding strips equivalent to the flanges, for example 11a, 12a may be utilized in joining adjacent wall portions by cementing or otherwise securing the wall portions in position.

70

75

It is understood in this connection that the flanges such as 11a, 12a are secured to adjacent wall parts by cementing, gluing or the like in accordance with conventional practices in securing adjacent wall parts together in constructing luggage.

In utilizing the single-faced worksheet it will be apparent that the single facing 11 may be disposed on the inner and outer surface of the resulting product, but as a general rule would be used externally in the construction of luggage.

Having fully described my invention, what I claim as new and desire to secure by Letters Patent, is:

- 15 1. The herein described method of forming plywood products of the character described which consists in using a thin plyboard, saturating both surfaces of the board with a soda solution, then applying a paste to a fabric sheet, 20 then arranging the sheet thus treated upon the saturated board and smoothing said sheet over the board to lie snugly thereon, then immediately placing the board covered with said sheet in a suitable shaping means to bend or fold pre- 25 determined sections or areas thereof into a pre-determined contour, then drying the same while supported in said means, and then removing the resulting product and utilizing the same for an intended purpose.

30 2. The herein described method of forming plywood products of the character described which consists in using a thin plyboard, saturating both surfaces of the board with a soda solution, 35 then applying a paste to a fabric sheet, then arranging the sheet thus treated upon the saturated board and smoothing said sheet over the board to lie snugly thereon, then immediately placing the board covered with said sheet in a suitable shaping means to bend or fold pre- 40 determined sections or areas thereof into a pre-determined contour, then drying the same while supported in said means, then removing the resulting product and utilizing the same for an intended purpose, arranging edge portions of 45 the fabric sheet beyond corresponding edge portions of said board to form coupling flanges, and utilizing said flanges as a means for joining the product to adjacent supports in the construction of predetermined articles of manufacture.

50 3. The herein described method of forming plywood products of the character described which consists in using a thin plyboard, saturating both surfaces of the board with a soda solution, 55 then applying a paste to a fabric sheet, then arranging the sheet thus treated upon the saturated board and smoothing said sheet over the board to lie snugly thereon, then immediately placing the board covered with said sheet in a suitable shaping means to bend or fold pre- 60 determined sections or areas thereof into a pre-determined contour, then drying the same while supported in said means, then removing the resulting product and utilizing the same for an intended purpose, arranging edge portions of 65 the fabric sheet beyond corresponding edge portions of said board to form coupling flanges, utilizing said flanges as a means for joining the product to adjacent supports in the construction of predetermined articles of manufacture, 70 and arranging and securing a facing sheet to each side of said plyboard.

75 4. The herein described method of forming plywood products of the character described which consists in using a thin plyboard, satu-

each side of said plywood. 4. The herein described plywood products of the which consists in using a method of forming character described thin plywood, sat-

rating both surfaces of the board with a soda solution, then applying a paste to a fabric sheet, then arranging the sheet thus treated upon the saturated board and smoothing said sheet over the board to lie snugly thereon, then immediately placing the board covered with said sheet in a suitable shaping means to bend or fold predetermined sections or areas thereof into a predetermined contour, then drying the same while supported in said means, then removing the resulting product and utilizing the same for an intended purpose, arranging edge portions of the fabric sheet beyond corresponding edge portions of said board to form coupling flanges, utilizing said flanges as a means for joining the product to adjacent supports in the construction of predetermined articles of manufacture, arranging and securing a facing sheet to each side of said plyboard, and utilizing one facing sheet of a character contrasting to that of the other facing sheet.

5. The herein described method of producing reinforced plywood sheets adapted for use in producing workpieces of irregular contour and including sharply distorted sections or areas, 25 which consists in employing a thin plyboard composed of birch wood, thoroughly saturating both surfaces of the plyboard with a suitable colorless saturant, then securing a fabric facing sheet to one surface of the plyboard by utilizing 30 a paste adhesive agent including small portions of salt and ether, firmly pressing and smoothing the fabric facing sheet to said plyboard, then immediately placing the resulting product in a forming means, distorting the product thus formed by said forming means to the irregular contour patterned by said forming means, allowing the product to dry in the forming means, and then removing the same therefrom. 35

40
6. The herein described method of producing
reinforced plywood sheets adapted for use in
producing workpieces of irregular contour and
including sharply distorted sections or areas,
which consists in employing a thin plyboard
composed of birch wood, thoroughly saturating
both surfaces of the plyboard with a suitable
colorless saturant, then securing a fabric facing
sheet to one surface of the plyboard by utilizing
a paste adhesive agent including small por-
tions of salt and ether, firmly pressing and
smoothing the fabric facing sheet to said ply-
board, then immediately placing the resulting
product in forming means, distorting the prod-
uct thus formed by said forming means to the
irregular contour patterned by said forming
means, allowing the product to dry in the form-
ing means, then removing the same therefrom,
and arranging predetermined portions of the
facing sheet beyond edges of said plyboard to
form coupling flanges on the resulting article
facilitating attachment of the article to prede-
termined supports.
45
50
55
60

7. The herein described method of forming integral angularly arranged wall parts of predetermined articles of manufacture which consists in providing a thin flat plyboard of the contour of the unitary wall parts to be formed, applying a fabric facing to at least one surface of said plyboard by first saturating the plyboard and then securing the facing thereto by means of a paste to establish a firm binding between the facing and said plyboard, then placing the board and fabric facing thus treated and united and while in the soft and pliable state in a pre- 75

determined forming means for producing the desired integral angularly arranged wall portions, drying the workpiece while maintained in said last named means, and then removing the finished product, consisting of angularly arranged unitary walls, therefrom.

8. The herein described method of forming integral angularly arranged wall parts of predetermined articles of manufacture which consists in providing a thin flat plyboard of the contour of the unitary wall parts to be formed, applying a fabric facing to at least one surface of said plyboard by first saturating the plyboard and then securing the facing thereto by means of a paste to establish a firm binding between the facing and said plyboard, then placing the board and fabric facing thus treated and united and while in the soft and pliable state in a predetermined forming means for producing the desired integral angularly arranged wall portions, drying the workpiece while maintained in said last named means, then removing the finished product, consisting of angularly arranged unitary walls, therefrom, and forming projecting flanges on the fabric facing for securing predetermined edges of the resulting product to adjacent supports in the construction of predetermined articles of manufacture.

9. The herein described method of forming box or case parts for predetermined articles of manufacture which consists in saturating a thin plyboard to soften the same, cementing a fabric facing to at least one surface of the plyboard while in its saturated and soft state, then shaping the product thus formed by a suitable mold to distort the soft sheet and board to form at least two angularly disposed walls of a box or case, allowing the product to dry to fixedly retain the angular walls in said angular relationship, and then securing said part of the box to another wall part or parts of a contour conforming with the edges of the angularly arranged walls of the first named part.

10. The herein described method of forming box or case parts for predetermined articles of manufacture which consists in saturating a thin plyboard to soften the same, cementing a fabric facing to at least one surface of the plyboard while in its saturated and soft state, then shaping the product thus formed by a suitable mold to distort the soft sheet and board to form at least two angularly disposed walls of a box or case, allowing the product to dry to fixedly retain the angular walls in said angular relationship, then securing said part of the box to an-

other wall part or parts of a contour conforming with the edges of the angularly arranged walls of the first named part, providing on predetermined edges of the first named part projecting flanges formed from the facing material employed, and extending said flanges onto the second named wall part in securing said parts together.

11. The herein described method of forming box or case parts for predetermined articles of manufacture which consists in saturating a thin plyboard to soften the same, cementing a fabric facing to at least one surface of the plyboard while in its saturated and soft state, then shaping the product thus formed by a suitable mold to distort the soft sheet and board to form at least two angularly disposed walls of a box or case, allowing the product to dry to fixedly retain the angular walls in said angular relationship, then securing said part of the box to another wall part or parts of a contour conforming with the edges of the angularly arranged walls of the first named part, providing on predetermined edges of the first named part projecting flanges formed from the facing material employed, extending said flanges onto the second named wall part in securing said parts together, and arranging projecting flanges of inner and outer fabric facing sheets of the first named part upon inner and outer surfaces of the second named part.

12. The herein described method of forming box or case parts for predetermined articles of manufacture which consists in saturating a thin plyboard to soften the same, cementing a fabric facing to at least one surface of the plyboard while in its saturated and soft state, then shaping the product thus formed by a suitable mold to distort the soft sheet and board to form at least two angularly disposed walls of a box or case, allowing the product to dry to fixedly retain the angular walls in said angular relationship, then securing said part of the box to another wall part or parts of a contour conforming with the edges of the angularly arranged walls of the first named part, providing on predetermined edges of the first named part projecting flanges formed from the facing material employed, extending said flanges onto the second named wall part in securing said parts together, and utilizing projecting flanges of the first named part to support reinforcing members at free edges of the first named part.

HERMAN J. RIES.
